UNITED STATES PATENT OFFICE

2,638,088

APPLIANCE FOR MASSAGING AND EXERCISING HUMAN FEET

Robert F. Johnson, Bedford, Va.

Application November 24, 1950, Serial No. 197,464

3 Claims. (Cl. 128—25)

1

This invention relates to exercising apparatus, and more particularly to a foot exerciser.

A main object of the invention is to provide a novel and improved foot-exercising device which is very simple in construction, which is easy to use, and which provides progressive muscular development of the arches and other portions of the feet.

A further object of the invention is to provide an improved foot-exercising device which is very inexpensive to manufacture, which is compact in size, which affords progressive development of the muscles of the feet in a painless manner, and by the use of which numerous ailments derived from foot weakness may be avoided.

Further objects and advantages of the invention will become apparent from the following description and claims, and from the accompanying drawings, wherein:

Figure 1 is a top plan view of an improved foot-exercising device constructed in accordance with the present invention;

Figure 2 is a side elevational view of the foot-exercising device of Figure 1;

Figure 3 is a perspective view showing the manner of using the device at the beginning of a course of foot exercises;

Figure 4 is a perspective view showing the manner of using the device at an intermediate stage of the course of foot exercises.

Referring to the drawings, the exercising device is designated generally at 11 and comprises a pair of parallel bar members 12 and 13 connected by a transverse bar member 14 secured to the intermediate portions of the bar members 12 and 13 and extending at right angles to said bar members 12 and 13. The bar member 13 is relatively small in height and has smoothly rounded top surfaces on opposite sides of the connection to the bar member 14, as shown at 15, 15. The bottom surface of bar member 13 is flat, as shown at 16, the bottom surfaces of the bar members 12 and 14 being similarly flat, as shown at 17 and 18. The flat surfaces 16, 17 and 18 are coplanar and enable the device to be supported in a very stable manner on the floor.

The top surfaces of bar member 12 on opposite sides of the transverse connecting bar 14 are rounded, as shown at 19, 19 in a manner similar to that of the surfaces 15, 15, and the bar member 12 is of substantially greater height than bar member 13. The transverse connecting bar 14 is also smoothly rounded at its top surface, but is formed with the spaced depre-

2

sions 20 and 21 having similar heights which are intermediate in value between the height of bar member 12 and the height of bar member 13. The depressions 20 and 21 are of substantial width and are separated by the intermediate, rounded hump or projection 22. Respective rounded shoulders 23 and 24 are defined at the ends of the transverse connecting bar 14.

The bar member 14 is connected to the parallel bar members 12 and 13 in any suitable manner for providing a rigid connection, as by suitable lap joints reinforced with glue or other fastening means. The bar members 12, 13 and 14 may be formed of wood, plastic, or any other suitable material, such as aluminum or similar light, durable and strong metal.

In using the device, the user first places his feet on the rounded top surfaces 15, 15 of the bar member 13, the user being in a standing position and holding onto a suitable support, such as a chair, the feet being rocked back and forth on the surfaces 15, 15 with said surfaces in engagement with the arch portions or the regions of the feet adjacent thereto. The degree of pressure should be gradually increased until the muscles of the feet have been somewhat toughened. After a few days of exercising the feet on the bar member 13 in the manner above described, the user may repeat the procedure on the transverse connecting bar 14, engaging the arch portions of the feet in the depressions 20 and 21 and rocking the feet on said arch portions for short periods of time for several days until the muscles of the feet become further conditioned and toughened to the increased stretching provided by the transition from the exercising bar 13 to the exercising bar 14. Figures 3 and 4 illustrate the manner in which the feet are engaged over the rounded top surfaces of the respective exercising bars 13 and 14.

After the feet have become conditioned to the exercise on the crossbar 14, the user may proceed to exercise the feet on the final exercising bar 12 which is of maximum height. As in the case of the two previous exercising bars, the user rolls or rocks on the top surfaces of bar 12 with the arches of the feet engaged on said top surfaces and the user being in a standing position. As in the previous exercisers, the user massages the arch portions of the feet on rounded top surfaces 19, 19 for short periods, repeated frequently over the course of several days until the muscles of the arches and adjacent portions of the feet have become conditioned and toughened to an extent wherein the

exercises may be carried on with a minimum degree of pain or discomfort over relatively long periods of time. When the feet have become strong enough so that the user can stand on the rounded projection 22 with one foot at a time and with all the weight of his body supported on said projection without pain or discomfort, the course of foot exercises may be considered as having been successfully completed.

It will be readily apparent that numerous variations in the manner of use of the above-described device may occur to persons employing the device, and that various other methods of exercising the feet on the device to provide progressive development and toughening of the foot muscles may be devised.

While a specific embodiment of an improved foot-exercising device has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. In a foot exerciser, a pair of substantially parallel bars spaced from each other, a third bar extending between said parallel bars and fixedly connected at its ends to said parallel bars at points spaced from the ends of the parallel bars, all of said bars having flat undersides arranged to rest upon a supporting surface, all of said bars having transversely rounded upper surfaces upon which feet are adapted to be rocked for exercise, the rounded upper surface of said third bar having longitudinally rounded hump means rising therefrom with which the inner and outer sides of arch portions of feet are adapted to be engaged while rocking feet on the upper surface of said third bar.

2. In a foot exerciser, a pair of substantially parallel bars spaced from each other, a third bar extending between said parallel bars and fixedly connected at its ends to said parallel bars at points spaced from the ends of the parallel bars,

5 all of said bars having flat undersides arranged to rest upon a supporting surface, all of said bars having transversely rounded upper surfaces upon which feet are adapted to be rocked for

10 exercise, the rounded upper surface of said third bar having longitudinally rounded hump means rising therefrom with which the inner and outer sides of arch portions of feet are adapted to be engaged while rocking feet on the upper surface of said third bar, said hump means comprising a plurality of humps spaced along said third bar.

15 3. In a foot exerciser, a pair of substantially parallel bars spaced from each other, a third bar extending between said parallel bars and fixedly connected at its ends to said parallel bars at points spaced from the ends of the parallel bars, all of said bars having flat undersides arranged to rest upon a supporting surface, all of said bars having transversely rounded upper surfaces upon which feet are adapted to be rocked for 20 exercise, the rounded upper surface of said third bar having longitudinally rounded hump means rising therefrom with which the inner and outer sides of arch portions of feet are adapted to be engaged while rocking feet on the upper surface of said third bar, said hump means comprising a plurality of humps spaced along said third bar, the upper surface of one of said parallel bars being depressed below the upper surface of the other parallel bar, and said hump being elevated 25 above the upper surface of said one parallel bar and substantially on a level with the upper surface of the said other parallel bar.

30 35 ROBERT F. JOHNSON.
